UNITED STATES PATENT OFFICE.

JOHN E. MITCHELL AND DENNIS PARKS, OF ST. LOUIS, MISSOURI.

HEEL-BUILDING MACHINE.

1,228,948.

Specification of Letters Patent. Patented June 5, 1917.

Application filed March 25, 1916. Serial No. 86,614.

To all whom it may concern:

Be it known that we, JOHN E. MITCHELL and DENNIS PARKS, citizens of the United States, residing in the city of St. Louis and State of Missouri, have invented new and useful Improvements in Heel-Building Machines, of which the following is a specification.

This invention relates to heel-building machines, wherein a number of lifts necessary for forming a heel-blank are successively delivered within easy reach of the operator and are then supplied with paste and assembled in a heel-former and afterward placed in a suitable holder. The said machine provides an inclined table which has mounted thereon a series of vertically-disposed magazines for containing stacks of lifts, and means for simultaneously ejecting the lowermost lift from each of the magazines. Located adjacent to the place of deposit of lifts ejected from said magazines is a pasting device, and beyond said pasting device, at the front of the machine, is a rocking carrier having heel-formers mounted thereon. On either side of the machine is a holder of indeterminate length for receiving the heel-blanks. After the pasted lifts are assembled in one of the heel-formers to form a heel-blank, the carrier is given a quarter turn to bring such heel-former into position opposite one of the heel-blank holders, and by operating the machine the heel-blank is forced from the heel-former into said holder. Preferably, two heel-formers are employed, so that as each heel-former is in position to have the lifts assembled therein the other is opposite one or the other of said holders. The heel-blank holders are of such length and size that as successive heel-blanks are forced therein, the column of heel-blanks will be placed under pressure and will be maintained under pressure by frictional contact of the lifts, or of the largest lift, of each heel-blank with the walls of the holder, and after the holder is full, as each fresh heel-blank is inserted a complete heel-blank, with the paste between the lifts thereof fully set, will be discharged from the rear end of the holder.

The lift-holding and delivering means and the pasting device illustrated in connection with the present machine, respectively form the subject-matter of separate applications for patent filed of even date herewith by John E. Mitchell, one of the present appli-

cants, serially numbered, respectively, 86,662 and 86,663, and filed March 25th, 1916.

The present invention is concerned more particularly with the lift-receiving and heel-blank delivering mechanism. The main object of the invention is to provide a carrier having a heel-former mounted thereon which latter normally occupies a position opposite and in line with a pasting device, and which is movable to carry the heel-former with the heel-blank built up therein opposite a holder of indeterminate length and to provide mechanism for ejecting the heel-blank from the heel-former into said holder. A further object, in carrying out such main object of the invention, is to provide, in combination with a pasting device and two heel-blank holders, a rocking carrier having two heel-formers mounted thereon in separated relation, the parts being so positioned relative to each other that as the carrier is rocked to bring one heel-former opposite the pasting device the other heel-former will be opposite one or the other of said holders; a further object of the invention relates to the provision of automatic means for preventing the heel-blank from sticking to or being retained in the heel-former as the latter is moved away from the mouth of the heel-blank holder after pressure has been applied to discharge the heel blank from the heel-former; and still further objects of the invention relate to details of construction and to combinations and arrangements of parts whereby the above stated objects of the invention are attained.

The invention is illustrated in the accompanying drawings, in which—

Figure 1 is a view in side elevation of a heel-building machine constructed according to our invention;

Fig. 2 is a vertical transverse sectional view of the same;

Fig. 3 is a fragmentary plan view on an enlarged scale and viewed in the direction of the arrow 3 of Fig. 1; and

Fig. 4 is a view in front elevation, also on an enlarged scale, and viewed in the direction of the arrow 4 of Fig. 1.

Referring now to the drawings, the frame of the machine is composed essentially of two side frame-members 1 and 2, which are connected toward their upper ends at front and rear by cross-beams 3. The frame-members 1, 2, are preferably mounted on bolsters 4, and their upper end portions 5

are inclined forward, or toward the operator. Each of the frame-members is provided in its upper end with a rectangular recess 6 which recesses receive a cross-beam 7, the opposite ends of which, as shown in Fig. 3, project beyond said frame-members. Supported on the top of the frame-members in front of the cross-beam 7 are table-sections 8, the outer ends of which are flush 10 with the ends of the cross-beam 7 and the inner ends of which are separated from each other to provide a rectangular opening 9, the rear end of which is closed by the forward edge of the cross-beam 7. Each of the frames 1 and 2 is provided in its top and forward side with a rectangular recess 10 which is adapted to receive a cross-beam 11 extending across the front of the machine, as shown more clearly in Figs. 3 and 20 4, and which is centrally recessed in its upper edge portion, as indicated at 12, to provide a continuation of the recess 9. To the rear of the cross-beam 7 there is mounted on the top of the side frame-members a table-section 13, said table-section, with the cross-beam 7, table-sections 8 and cross-beam 11 forming a top, or table, the upper surfaces of these parts being flush with each other, and the table as a whole being inclined downward, or toward the operator. Secured near opposite ends, respectively, of the cross-beam 7 are two standards 14 and 15, between which extend two rods 16 and 17, located, respectively, at the top and center of said standards, and having their opposite ends secured therein. The numerals 18 indicate a series of magazines, each of which, as shown by Fig. 3, is L-shaped in cross section, and affords a front wall 19 and a side wall 20. Mounted on the front wall 19 of each magazine is a bracket-member 21. Each of these bracket-members is provided toward each of its opposite ends with a slot 22 through which extends a screw-threaded bolt 23 passing through the front wall 19 of the magazine. A binding-nut 24 is mounted on the screw-threaded end of each of said bolts. Each of the brackets 21 is provided toward its upper end with a recessed seat 25, which is adapted to receive the rod 16. The numeral 26 indicates a clamping-plate, which is loosely mounted on a set-screw 27 having screw-threaded engagement with the bracket 21 about centrally thereof. Said clamping-plate has off-set ends 28 which are adapted to engage the respective rods 16 and 17, and, when the set-screw 27 is turned home, to draw the seats 25 of the brackets 18 into engagement with the rod 16 and the lower portions 29 of said brackets into engagement with the rod 17, whereby all of the magazines are supported on the rod 16 and are held in firm, fixed position by engagement of the brackets 21 with said rod and

the rod 17. By loosening the binding-nuts 24 the magazines 18 may be raised or lowered to remove their lower ends a greater or less distance from the table of the machine to provide a throat or passageway 30 for the passage of lifts under the magazines. The standards 14 and 15 and the magazines 18 supported thereby are perpendicularly-disposed with reference to the top of the machine, and hence are inclined forward, or toward the operator, as shown in the drawings. The side walls 20 of the respective magazines are parallel to each other, and, as clearly shown by Fig. 3, the several stacks of lifts 31 are retained between the side walls of adjacent magazines with their rounded ends resting against the front wall 19 of each magazine. In order to accommodate lifts of varying sizes provision is made for a lateral adjustment of the magazines 18, and this is accomplished by simply loosening the binding-screws 27 and sliding the magazines 18 over the rods 16 and 17 to the desired position, when the binding-screws 27 are again turned to clamp the magazines in the adjusted positions. By inclining the magazines, as described, it is possible to retain a stack of lifts in each magazine without the necessity of using a back wall. The advantage of this construction is fully set forth in the companion application of John E. Mitchell above referred to, and need not be recited more in detail. Slidably mounted on the table-section 13 at the rear of the machine is an ejector-plate 32 which is of a width to extend across all of the magazines and of a thickness to work in the space or throat 30 provided between the lower ends of the magazines and the table of the machine. The ends of the ejector-plate 32 are extended beyond the sides of the table-section 13 and are apertured to receive the upper ends of throw-levers 33, the lower ends of which are secured in crank-arms 34 having hubs 35 loosely mounted on opposite ends of a shaft 36 and secured in position thereon, as by means of collars 37 and set-screws 37a. The shaft 36 is mounted in suitable bearings in the standards of the side frame-members, and fixedly secured at one end centrally of said shaft is a foot-lever 38 which projects forward beyond the machine so that its free end is within easy reach of the foot of the operator. The foot-lever 38 is normally drawn upward by means of a coil spring 39, one end of which is secured to the foot-lever and the other end to a rod 40 extending between the frame-members 1 and 2 and secured at its ends therein. When the foot-lever is depressed by the operator the throw-levers 33 will be moved forward, by mechanism later described, carrying the ejector-plate 32 under the magazines 18, the former engaging and ejecting the lower lift in each 130

of the magazines and moving them out upon the top or table of the machine within easy reach of the operator. To build the heel-blanks the lifts first have paste applied thereto and are then assembled successively in the heel-forming devices as hereinafter described. The pasting device comprises a receptacle 41 removably mounted at one end on a support 42 secured to the under side 5 of the cross-beam 11 and at its other end on the rear cross-beam 3 extending between the side frames. Mounted in bearings in the side frames of the machine is a shaft 43, one end of which is provided with a pulley (not shown) by means of which it may be rotated. Secured on this shaft is a pasting roller 45 which is provided with annular circumferential recesses 46 through which extend two parallel bars 47 which 10 are secured at their inner ends to the cross-beam 7 and at their forward ends are secured to opposite sides of a lug 48 extending upward from a plate 49 secured on the bottom of the recess 12, as shown more 15 clearly in Fig. 3. The roller 45 is constantly revolved by the shaft 43 and takes up the paste supplied to the receptacle 41. In practice the upper edges of the bars 47 are substantially flush with the periphery 20 of the roller 45 and with the upper surface 25 of the top of the machine. The forward ends of these bars extend above the lug 48 to which they are secured, and terminate flush with the outer edge of the cross-beam 30 35 11. As the paste used in the receptacle 41 is relatively thick the layer of paste adhering to the roller will project slightly above the upper edges of the bars 47 and when one of the lifts 31 is moved by the 40 operator over the bars 47 its under side will be thoroughly and evenly supplied with paste by the roller 45.

In order to prevent the lowermost lifts from being carried backward and out of the 45 magazines in the return movement of the ejector-plate 32, a bar 50 is provided having its opposite ends 51 bent at right angles and provided each with a slot 52 by means of which the ends 51 are adjustably secured 50 to the respective standards 14 and 15, by the use of set-screws 53. The bar 50 is located at the rear of the magazines 18 and extends across the same, as shown in Fig. 3, in close proximity to the rear sides thereof, 55 preferably being angularly disposed or inclined relative to the rear side of the magazines, as shown by Fig. 2, so as to have its point of closest approach to the magazine opposite the throat 30, and thereby avoid 60 the possibility of offering an obstruction to the downward movement of the lifts in the event one or more of them should project slightly beyond the others. Should the ejector-plate 32 in its return movement tend 65 to carry the lowermost lifts resting there-

on backward with it, said lifts would engage the lower edge of the bar 50 and be prevented from such movement. By loosening the set-screws 53 the bar 50 may be adjusted toward or from the magazines according as the sizes of lifts used are varied. Each end of the bar may be independently adjusted to give the bar an inclined relation to the magazines where a number of lifts are used which vary in size from a relatively large lift to a very small lift. We have illustrated only five magazines accommodating four stacks of lifts. It will be apparent, however, that a greater or less number of magazines may be used according to the height of the heel-blanks to be built. The numerals 54 (Fig. 4) indicate brackets, which are bolted, respectively, to the front and rear of each of the side frames 1, 2, as indicated at 55. The brackets on each side of the machine are in line with each other, but owing to the inclination of the upper portion of the side members the rear brackets 54 are at a greater distance from the base of the machine than the front 70 75 80 85 90 95 100 105 110 115 120 125 130

brackets 54. Each of the brackets is provided at its lower end with an upstanding projection 56 and extending between and secured at their opposite ends to opposite sides of the projections, as by means of bolts 57, are two parallel rails 58. At its upper end each of the brackets 54 has an arm 59 extending outward at right angles to the frame and provided with a bearing 60. The numeral 61 indicates a relatively long, transversely-curved plate, which has secured on its upper side, at its front end, and at some distance removed from its rear end, respectively, two pins 62 which slidably engage in the bearings 60 of the front and rear brackets at each side of the machine. It will be understood that the construction of the brackets and the parts supported thereby is the same at each side of the machine, and the constructions provide two 110 holders consisting of the rails 58 and the curved top plate 61 which are adapted to receive between them heel-blanks 63, as shown more clearly in Fig. 4. The rails 58 project beyond the end of the plate 61 for 115 a purpose presently set forth. The heel-blanks are inserted in the holder with their flat edge or breasts resting on the rails 58 so that the curved plate 61 may engage their rounded sides. The plate 61 rests upon the 120 heel-blanks and exerts a greater or less pressure thereon according to the weight of the said top plate. The pressure exerted on the heel-blanks produces the necessary frictional resistance to the movement of the heel-blanks through the holders, whereby the pressure applied in moving the column of heel-blanks through the holder will result in placing all of the heel-blanks under compression, and they will be held under such 130

compression until discharged from the holders. Rotatably and slidably mounted in suitable bearings 64 provided centrally of the two cross-beams 3 is a shaft 65, which, as shown particularly by Fig. 2, projects a considerable distance beyond the front end of the machine. The numeral 66 indicates a yoke-member which spans the forward cross-beam 3 and is provided at its opposite ends with bearings 67 and 68, respectively, which receive the shaft 65 and in which said shaft is free to rotate. Secured on the shaft 65 adjacent to the rear bearing 67 is a collar 69 which prevents longitudinal movement of the yoke-member 66 toward the rear end of the shaft 65. Mounted on opposite sides of this rear bearing 67 are trunnions 70. The numeral 71 indicates a bell-crank lever which is fixedly secured on a shaft 72 extending across the machine and mounted at its ends in bearings 73 provided in the side frame-members 1 and 2. One arm of this bell-crank lever is in the form of a yoke 71^a which embraces the bearing 67 and the respective members of which are slotted at their outer ends, as indicated at 74 (Fig. 1) to receive the trunnions 70. The other arm of the bell-crank lever 71 is pivotally connected at 75 (Fig. 2) to the upper end of a connecting rod 76, the lower end of which is pivotally connected at 77 to the foot-lever 38 intermediate the ends of the latter. Toward the outer ends of the shaft 72 are fixedly secured crank-arms 78 (Figs. 1 and 2) the outer ends of which are pivotally connected at 79 to the ends of connecting rods 80, the opposite ends of which are pivotally connected at 81 to the respective throw-levers 33. The members of the yoke 71^a of the bell-crank lever 71 are provided with set-screws 82 respectively, which are turned into engagement with the opposite sides of the yoke-member 66 and thereby prevent said yoke-member from turning. The numeral 83 (Fig. 4) indicates a rocking carrier which is in the form of a bell-crank lever having arms 84 and 85 extending at right angles to each other and connected to a hub 86 (Figs. 1 and 2). This hub is mounted on the outer end of the shaft 65 and fixedly secured thereon by means of a set-screw 87. The hub 86 is located adjacent to the bearing 68 of the yoke-member 66 (see Fig. 2), and acts as a thrust-bearing for the yoke-member 66 in moving the carrier 83 and shaft 65 outward in the operation of the machine, as later explained. The outer end of each of the arms 84 and 85 is provided with a cylindrical bearing 88. The numeral 89 indicates the back-plate of a heel-former, one of which is mounted on each of the arms 84, 85, by means of a wrist-pin 90 secured on the front face of said back-plate and rotatably mount-

ed in the bearing 88, and secured therein by means of a collar 91 mounted on the end of said wrist-pin and fastened thereon by means of a set-screw 92. Secured to and projecting inward from each back-plate 89 are two bars 93 which form the bottom of the heel-former and when the latter is opposite the pasting device, as shown by Fig. 3, are in line with and substantially form continuations of the rails 47, their upper edges being flush with the upper edges of said rails, the latter feature being more clearly illustrated in Fig. 1. Mounted near opposite sides of each of the back-plates 89 are guide-members 94, which are adjustable in slots 95 formed in said back-plate (Fig. 4) the guide-members having screw-threaded ends extending through said slots and being provided with jam-nuts 96. By loosening these jam-nuts the guide-members 94 can be moved closer together or farther apart according to the width of the lifts being employed for building the heel-blank. The guide-members 94 have their inner edges outwardly inclined, as shown by Fig. 3, and serve as the sides of the heel-former, and insure the correct positioning of the lifts as they are forced into the heel-former, as will be clearly understood by those skilled in the art. Each of the back-plates 89 has at its outer end an integral depending arm 97 to which is pivotally secured at 98 the upper end of a connecting rod 99, the lower ends of which arms 99 are pivotally secured at 100 to the front of the yoke-member 66 at opposite sides thereof. Each of the wrist-pins 90 is provided with a longitudinal aperture which also extends through the back-plate 89, and in this aperture is slidably mounted an ejecting-pin 101 (see Figs. 1 and 2), the outer end of each of which pins is pivotally connected at 102 to the outer end of a floating lever 103. Each of the arms 84, 85, is provided near the hub 86 with a cylindrical enlargement 104 which is apertured to slidably receive a contact-pin 105, the outer end of which is pivotally connected at 106 to the lower end of the floating lever 103. Each of the floating levers 103 is provided on its inner side with a lug 107 for engagement with the outer side of the respective arms 84 and 85, and above this lug it is off-set or curved outwardly, as indicated at 108, to extend beyond the outer end of the wrist-pin 90. Below the lug 107 each of the floating levers 103 has secured thereto one end of a coil spring 109 which spring is housed in an apertured enlargement 110 provided in the respective arms 84 and 85, and has its inner end secured, as at 111, on the inner side of its arm.

In operation one or the other of the arms 84, 85, being in the vertical position shown in the drawings, with its heel-former ad-

ja cent the support for the lifts, the attendant presses down the foot-lever 38, which operation actuates the bell-crank lever 71 to move the yoke-member 66 to the rear, and 5 the bearing 67 of the latter engaging the collar 69 on the shaft 65 moves the latter to the rear with it, thereby also moving inward the arm 84 or 85 to the position shown in Figs. 1 and 3, in which the inner 10 ends of the bars 93, forming the bottom of the heel-former, will lie directly opposite the outer ends of the rails 47 of the pasting device. This movement of the bell-crank lever 71 also rocks the shaft 72 which, 15 through the crank-arms 78 and connecting- rods 80, serves to throw the upper ends of the levers 33 inward moving the ejector plate 32 under the magazines 18 and forcing the lowermost lift in each of said maga- 20 zines through the throat 30 to a position on the top of the cross-beam 7 which, as stated, forms a portion of the top of the machine. The operator first places the bottom or smallest lift to be used, which does not re- 25 quire to be pasted, in the heel-former and then, taking the lifts deposited on the table in the order in which they are to be assembled, moves them rapidly over the rails 47 which constitute a slideway, in 30 which operation the roller 45, which travels in the direction of movement of the lifts, that is, toward the operator, will apply paste to the under side of each lift as it is moved over the slideway. After passing over the 35 pasting roller the lift is turned up on its flat edge or breast, as indicated by the dotted lines in Fig. 1, and pressed into the heel-former between the guide-members 94, this operation being continued until the 40 number of lifts necessary to complete the heel-blank has been deposited in the heel-former. During this operation the foot-lever 38 will be held depressed. Upon completion of the heel-blank the foot-lever 38 45 is released and is drawn upward by the spring 39. In this movement the upper ends of the levers 33 will be drawn outward to carry the ejector-plate 32 beyond the rear sides of the magazines, and the bell-crank 50 lever 71 will be actuated to throw the yoke-member 66 toward the operator, in which movement its bearing 68 will engage the hub 86 of the rocking carrier 83 and move the latter, with the shaft 65, outward to 55 the position shown in Fig. 2. Assuming the arms 84 and 85 to be in the position shown in Fig. 4, the operator next places his hand upon the arm 84 and rocks the carrier 83 to the left to bring its heel-former 60 with the completed heel-blank therein into a position remote from the support and opposite the mouth of the holder at the left of the machine, as shown in Fig. 4, and at the same time move the heel-former on the 65 arm 85 opposite the pasting device. It is necessary in this movement of the rocking carrier 83 that the heel-blank 63 be maintained in the position shown in the drawings, that is to say, with its rounded side upward, so that it may be inserted in the 70 holder with its flat or breast side resting on the rails 58; and this is accomplished through the medium of the connecting-rods 99 which operate to hold the back-plate in a horizontal position, the wrist-pin 90 of 75 each heel-former in the movement described turning in the respective bearings 88. The heel-former with the heel-blank therein having been brought opposite to the holder as described, the foot-lever 38 is again de- 80 pressed, thereby operating the ejector-plate 32 and the rocking carrier 83 in the manner previously described, and in such movement the heel-blank is forced into the holder, that is to say, between the plate 61 and the rails 85 58 and at the same time the end of the contact-pin 105 engages the face of the forward cross-beam 3 and moves the inner end of the floating lever 103 outward against the resistance of the spring 109, which latter 90 forms a movable pivot causing the inner end of the pin 101 to come in contact with the heel-blank. When the foot-lever 38 is again released the rocking-lever 83 is moved outward, as previously described, carrying 95 the heel-former from about the lift which has been deposited in the holder. As the rocking carrier moves outward the power of the spring 109 is sufficient to force the pin 101 inward and prevent the heel-blank from ad- 100hering to or remaining wedged in the heel-former. The position of the floating lever 103 when the rocking carrier 83 is in its inward position is shown in Fig. 3, and its position when the rocking carrier has been 105 moved outward, is shown in Figs. 1 and 2. In these latter figures, however, the floating lever is shown in connection with the heel-former that is opposite the pasting device, and not that which is opposite a 110 heel-blank holder. The position of the parts is exactly the same, however, except that in the latter case there would be no heel-blank in the holder. As soon as the rocking carrier has moved far enough to withdraw the end of the pin 105 from contact with the machine, the spring 109 draws the floating lever inward, and as the lug 107 comes in contact with the arm 84 or 85, it forms a fulcrum which causes the inner 115 end to be moved into contact with the arm, and the pin 101 to be moved outward to carry its inner end beyond the forward face of the back-plate 89. It will be understood that, in operation, the rocking carrier 83 120 is turned first to one side and then to the other so that as one of the heel-formers is opposite one or the other of the holders, the other heel-former is opposite the pasting device. The motion of the rock- 125 130 135

ing carrier 83 in either direction is arrested by the bottom of the back-plate 89 coming in contact with and resting upon the rails 58, more clearly shown to the right in Fig. 4, and in this position the bottom members 93 of the heel-former lie between the rails 58 with their upper surfaces flush with the upper surfaces of said rails, as shown by the dotted lines in said Fig. 4.

10 We claim:

1. In a heel-building machine, in combination with a support for lifts and a holder for receiving heel-blanks and maintaining them under pressure, a carrier having a heel-former mounted thereon and adapted to be moved alternately to positions opposite said support and opposite and adjacent to the receiving end of said holder, whereby heel-blanks may be forced directly into said holder by pressure used to discharge the heel-blanks from said heel-former.

2. In a heel-building machine, in combination with a support for lifts and a holder for receiving heel-blanks, a carrier having a heel-former mounted thereon and adapted to be moved alternately to positions opposite said support and opposite and adjacent to the receiving end of said holder, and means for discharging a heel-blank under pressure from the heel-former directly into said holder.

3. In a heel-building machine, in combination with a pasting device and a holder for receiving heel-blanks, and maintaining them in column formation, a carrier having a heel-former mounted thereon and adapted to be moved alternately to positions opposite said pasting device and said holder.

4. In a heel-building machine, in combination with a pasting device and a holder for receiving heel-blanks, and maintaining them in column formation, a rocking carrier having a heel-former mounted thereon and adapted to be turned alternately to positions opposite said pasting device and said holder.

5. In a heel-building machine, in combination with a support for lifts, a pasting device mounted in said support, holders for receiving heel-blanks located on either side of said pasting device, a carrier having heel-formers mounted and adapted to be rocked alternately in opposite directions to bring the respective heel-formers simultaneously opposite and in line with the pasting device and opposite and in line with one of said holders, and means for reciprocating said carrier.

6. In a heel-building machine, in combination with a pasting device and a holder of indeterminate length for receiving heel-blanks, a carrier having a heel-former mounted thereon and adapted to be moved

alternately to positions opposite said pasting device and said holder.

7. In a heel-building machine, in combination with a pasting device and a holder of indeterminate length for receiving heel-blanks, a rocking carrier having a heel-former mounted thereon and adapted to be turned alternately to positions opposite said pasting device and said holder, and means for discharging a heel-blank from the heel-former into said holder.

8. In a heel-building machine, in combination with a pasting device, holders of indeterminate length for receiving heel-blanks located on either side thereof, and a carrier having heel-formers mounted thereon and movable alternately in opposite directions to bring the respective heel-formers simultaneously opposite the pasting device and one of said holders.

9. In a heel-building machine, in combination with a pasting device, holders of indeterminate length for receiving heel-blanks located, respectively, at either side of said pasting device, a rocking carrier having arms disposed at an angle to each other, and a heel-former carried by each arm, said heel-formers normally occupying, respectively, positions opposite said pasting device and one of said holders, and said carrier being movable through the arc of a circle in one direction or the other to bring the heel-former opposite one holder to a position opposite said pasting device and the heel-former opposite the pasting device to a position opposite the other holder.

10. In a heel-building machine, in combination with a pasting device, a pair of holders of indeterminate length for receiving heel-blanks and located, respectively, on opposite sides of the machine, and a rocking carrier having arms extending at right-angles to each other and each of which has mounted on its outer end a heel-former, said heel-formers being normally positioned the one opposite the pasting device and the other opposite one of said holders, and said carrier being movable alternately in opposite directions through the arc of a circle to position each heel-former alternately opposite the pasting device and one of said holders.

11. In a heel-building machine, in combination with a pasting device, a pair of holders of indeterminate length for receiving heel-blanks and located, respectively, on opposite sides of the machine, a rocking carrier having arms extending at right-angles to each other and each of which has mounted on its outer end a heel-former, said heel-formers being normally positioned the one opposite the pasting device and the other opposite one of said holders, and said carrier being movable alternately in opposite

directions through the arc of a circle to position each heel-former alternately opposite the pasting device and one of said holders, and means for limiting the movement of the 5 carrier in either direction.

12. In a heel-building machine, in combination with a pasting device, a holder of indeterminate length for receiving heel-blanks, a carrier having a heel-former mounted thereon and movable to position the heel-former alternately opposite the pasting device and the holder, and means for reciprocating said carrier to force the heel-blank carried thereby into said holder. 10
13. In a heel-building machine, in combination with a pasting device, a holder of indeterminate length for receiving heel-blanks, a rocking carrier having a heel-former mounted thereon and movable in either direction through the arc of a circle to alternately position a heel-former opposite said pasting device and said holder, and means for maintaining the heel-former in an upright position irrespective of the position of 20 said carrier. 25

14. In a heel-building machine, in combination with a pasting device, a holder of indeterminate length for receiving heel-blanks, a carrier having a heel-former pivotally mounted thereon and movable in either direction through the arc of a circle to alternately position the heel-former opposite said pasting device and said holder, and means pivotally connecting said heel-former 30 and a fixed part of the machine whereby in the movement of the carrier the heel-former will always be maintained in an upright position. 35

15. In a heel-building machine, in combination with a pasting device, a holder of indeterminate length for receiving heel-blanks having its bottom projecting beyond its forward end, and a rocking carrier having a heel-former mounted thereon and movable 40 in either direction through the arc of a circle to alternately position the heel-former opposite said pasting device and said holder, the bottom of said heel-former being adapted to engage the projecting bottom of said 45 holder to arrest the movement of the carrier and position the heel-former opposite the holder. 50

16. In a heel-building machine, in combination with a pasting device, a holder of indeterminate length for receiving heel-blanks and having its bottom formed of rails projecting beyond the end of the holder, a carrier, a heel-former mounted on said carrier and having its bottom adapted to pass between the rails of said holder, the carrier being movable in either direction through the arc of a circle to alternately position said 55 holder opposite said pasting device and said former, and a member on said carrier adapt-

ed to engage the projecting portions of said 65 rails to arrest the movement of the carrier and to position the heel-former opposite said holder with the upper surface of said bottom flush with the upper surface of said rails. 70

17. In a heel-building machine, in combination with a pasting member, a slideway for supporting lifts passed over said pasting member, a holder for receiving heel-blanks, a carrier, a heel-former mounted 75 thereon and having a bottom for supporting the breasts of the lifts, said carrier being movable in either direction to alternately position said heel-former opposite said pasting device and said holder, and means for reciprocating said carrier in one position to bring the inner end of the bottom of said heel-former close to the outer end of said slideway, and in the other position of the carrier to force the heel-blank 80 carried by the heel-former into said holder. 85

18. In a heel-building machine, in combination with a pasting roller having circumferential grooves, a plurality of fixed slide rails passing through said grooves for supporting lifts passed over said pasting roller, a holder for receiving lifts having its bottom formed of a plurality of rails projecting beyond the end of the holder, a carrier, a heel-former pivotally mounted on said carrier and having its bottom formed of a plurality of bars, said carrier being movable in either direction to alternately position the heel-former opposite said pasting member 90 and said holder, the upper edges of the bars of said heel-former in the former position being flush with the upper edges of said slide rails, and said bars in the latter position being adapted to pass between the projecting ends of the rails of said holder, means for arresting the movement of the carrier in the latter position with the upper surface of said bars flush with the upper surface of said rails, and means for reciprocating said carrier when the heel-former 95 is in either of the described positions. 100

19. In a heel-building machine, in combination with a pasting device, a holder for receiving heel-blanks, a carrier having a heel-former mounted thereon and movable in either direction to alternately position the heel-former opposite said pasting device and said holder, means for reciprocating the carrier to force a heel-blank from its heel-former into said holder, a push pin mounted in said heel-former, a floating lever connected at one end to said push pin, a spring connected to said floating lever intermediate its ends, and a contact member carried by said lever and adapted when the carrier is moved toward the holder to engage a fixed part of the machine and place said spring under compression, whereby as the 110 115 120 125

carrier is moved away from the holder said spring will draw the push pin inward to engage a heel-blank and prevent its withdrawal with the heel-former.

5 20. In a heel-building machine, in combination with a support for lifts, a holder for receiving heel-blanks and maintaining them in column formation, and a carrier having a heel-former mounted thereon and adapted to be moved successively to positions opposite said support and said holder.

10 21. In a heel-building machine, in combination with a pasting device, a holder for receiving heel-blanks and maintaining them in column formation, and a carrier having a heel-former mounted thereon and adapted to be moved successively to positions opposite said pasting device and said holder.

15 22. In a heel-building machine, in combination with a support for lifts and a holder for receiving heel-blanks, a carrier having a heel-former mounted thereon and adapted to be moved alternately into a posi-

tion opposite and adjacent said support, and into a position opposite and adjacent to the 25 receiving end of said holder and remote from said support, and means for discharging a heel-blank under pressure from the heel-former directly into said holder.

20 23. In a heel-building machine, in combination with a support for lifts, an elongated holder open at both ends for receiving heel-blanks, and a carrier having a heel-former mounted thereon and adapted to be moved alternately into a position opposite 35 and adjacent said support, and into a position adjacent to and opposite an open end of said holder and remote from said support.

In testimony whereof, we have hereunto set our hands.

JOHN E. MITCHELL.
DENNIS PARKS.
